BOOK-BINDING APPARATUS

William E. Hicks, Conover, Wis.

Application February 8, 1956, Serial No. 564,265

3 Claims. (Cl. 11—1)

This invention relates to book-binding apparatus, and more particularly to such apparatus for binding loose-leaf books.

Among the several objects of the invention may be noted the provision of simple and rugged book-binding apparatus designed to reduce the labor and time required for loose-leaf book binding. Other objects and features will be in part apparent and in part pointed out hereinafter.

The invention accordingly comprises the elements and combinations of elements, features of construction, and arrangements of parts which will be exemplified in the structures hereinafter described, and the scope of which will be indicated in the following claims.

In the accompanying drawings, in which one of various possible embodiments of the invention is illustrated,

Fig. 1 is a diagrammatic top plan view, parts being broken away, of apparatus embodying my invention;

Fig. 2 is a front elevation of Fig. 1;

Fig. 3 is an enlarged detail view of certain pin links, parts being broken away;

Fig. 4 is an enlarged cross section taken on line 4—4 of Figs. 1 and 3, showing a pin link with an applied hollow threaded binding post or bushing;

Fig. 5 is a view similar to Fig. 4, but being taken on line 5—5 of Fig. 1 and showing the application to hollow threaded binding posts or bushings of a first cover;

Fig. 6 is a view similar to Fig. 5 but being taken on line 6—6 of Fig. 1 and showing the application to said hollow threaded binding posts or bushings of certain insert pages;

Fig. 7 is a view similar to Fig. 6 but being taken on line 7—7 of Fig. 1 and showing the application of a second cover to said hollow threaded binding posts or bushings and also showing the application thereto of a holding screw;

Fig. 8 is a view similar to Fig. 7 but showing a holding screw being driven into final position;

Fig. 9 is a view similar to Fig. 8 but showing a cross section of the finished loose-leaf book removed from the apparatus;

Fig. 10 is a plan view showing alternative forms of pin links; and,

Fig. 11 is an enlarged detail section taken on line 11—11 of Fig. 1.

Corresponding reference characters indicate corresponding parts throughout the several views of the drawings.

The assembly of loose-leaf books constituted by front and back covers with page inserts held together by means of hollow threaded binding posts or bushings and holding screws is tedious and time-consuming and makes relatively less profitable the production of such books in quantity. By means of the present invention, such books may be readily neatly assembled in large numbers at high speed and low cost.

Referring now more particularly to the drawings, there

is shown at numeral 1 a bed supported upon legs 3, two of which carry a platform 5. Upon the platform 5 is a driving motor 7 which, through a belt 9, drives a gear-reduction box 11. Through a belt drive 13, the box 11 drives a shaft 17 upon which is a wide drum or pulley 19. The shaft 17 is supported in bearings 21 upon a bracket 23 located at one end of the machine. At the other end is located a similar bearing bracket 25 carrying bearings 27 for an idler shaft 29. Shaft 29 supports a wide idler drum or pulley 31. The pulleys 19 and 31 are grooved as shown at 33 and support a thick flexible belt 34, composed of a material such as synthetic rubber or the like.

Supported on opposite sides of the belt, in symmetrical arrangements, are groups of preferably five right-angular guides or lugs 35 and 37. As shown in Fig. 11, each of these guides 35 and 37 is slotted on one side as shown at 39 for adjustable fastening to the belt 34. Fastening is accomplished by means of nut and bolt combinations 41. The guides 35 may be considered to be lateral guides, and guides 37 to be transverse guides. Within each group of guides 35, 37 is located a pair of leveling supports 43.

Positioned along the approximate center line or median line of the belt is a flexible chain 45, composed of pinned links 47 such as shown in Fig. 3. Their pins are shown at 49. Each link has in it a threaded hole 51. The median position of the chain 45 establishes first and second working areas on the belt 34 on opposite sides of the chain. The first working area is, for example, along the side of the belt corresponding to stations B, D, F, and the second working area is, for example, along the side corresponding to stations A, C, E, all of said stations to be referred to below.

35 The chain 45 is anchored at intervals to the belt 34 by means of screws such as shown at 53. These are threaded into appropriate holes 51. The pulley grooves 33 accommodate passage of the various heads of fastening means for the guides and chain. The chain between the fastening means 53 flexes with the belt as it passes over the pulleys.

At proper intervals along the chain 45, holes 51 in certain of its links 45 are provided with vertical pins 55, pairs of pins being symmetrically disposed with respect to the groups of guides 35, 37. These pins are for slidably accepting hollow threaded binding posts or bushings 57. The latter have endwise heads 59 and are threaded interiorly as shown at 61 (see Fig. 4).

50 Straddling the belt 34 is a support 63 for an electric torque-limited screw driver 65. This is carried on an extensible support 67, so that it may be raised and lowered manually for application to headed screws 69 such as shown in Fig. 7.

55 Operation is as follows, assuming that operators are located at stations A, B, C, D, E and F, and that the motor 7 is running. The belt travels at medium speed in the direction shown by the arrows.

An operator at A telescopically applies a pair of hollow threaded binding posts or bushings 57 to an appropriate pair of pins 55 (Fig. 4).

At station B (Fig. 5), a second operator applies to these hollow threaded binding posts or bushings 57 a back cover 71. This is prepunched for the purpose, as shown at 73, and has a transverse score line 75.

60 At station C (Fig. 6) an operator applies a prepunched sheaf of insert pages 77. Their punchings are shown at 79. This sheaf then becomes supported upon the elevated margin to the cover adjacent score line 75. The supports 43 are for the purpose of supporting all parts of the sheaf at equal elevations so as to avoid their riffling.

65 At station D (Fig. 7) an operator applies a second

front cover 81 to the hollow threaded binding posts or bushings 57 at prepunched holes 83. This cover is scored at 78.

At station E (Fig. 7), the screws 69 are manually applied to and given a threading start in the hollow threaded 5 binding posts or bushings 57.

When the assembly of Fig. 7 arrives at station F (Fig. 8), the bit 84 of electric screw driver 65 is applied to the screw slots so as to drive the screw heads 85 against the ends of the bushings 57. The pins 55 are short enough 10 to allow this.

Finally, the covered sheaves or completed books move to the pulley 19; at which point there is located a group of spring fingers 87 mounted on an extension 89 from bracket 23 and arching over the belt 34 over pulley 19, 15 being in staggered relation to the guide means 35 and the chain 45, as the drawings show. As the pins 55 and guides 35, 37 descend around the pulley 19, the leading margins of the covers 71, 81 and sheaf inserts 77 are upheld by these fingers where they may be taken off by an 20 operator, or fall on a table or container for inspection and packing.

It is apparent that as the pins 55 descend, they are telescopically retracted from the interiors of the bushings 57. It will be understood that the fits between the pins 55 and the threaded insides 61 are loose enough to permit such retraction. The fact that the pins 55 are carried upon a 25 chain link such as 47 also facilitates this retraction, since the chain is not required exactly to follow the curvature of the belt in passing over pulley 19, as might otherwise 30 too severely angle the pins and interfere with retraction. The spring fingers 87 also hold up the advancing books, so that they are not pulled down at this point. The cover 35 71 and 81 after discharge or by manual removal are folded over the sheaf 77, as shown in Fig. 9.

It sometimes occurs that spacings of the pair of pins 55 should be different from that afforded by the full-pitch distances between the pin holes 51 in the links 47. To this end, half links 91 may be used in the chain 45 at the appropriate intervals (as illustrated in Fig. 10), in order to bring about a half-pitch variation in the spacing between pins 55. In such event, appropriate adjustments at slots 39 of the guides 35 on the belt may be required for proper punch-hole alignment. The slots 39 in guides 37 permit of further adjustments for punch-hole alignments with pins 55. Slots 93 are also provided in the bracket 25 for permitting adjustments of the bearings 27 in order 40 properly to tension the belt 34.

In view of the above, it will be seen that the several 50 objects of the invention are achieved and other advantageous results attained.

As various changes could be made in the above constructions without departing from the scope of the invention, it is intended that all matter contained in the above description or shown in the accompanying drawings shall 55 be interpreted as illustrative and not in a limiting sense.

I claim:

1. Book-binding apparatus comprising a pair of pulleys and an endless flexible belt trained around the pulleys, the pulleys being arranged so that the belt has a generally 60

level upper reach, means adapted to drive the belt, a flexible chain of pinned links affixed to the belt on its outside in a median plane thereof and adapted to travel and flex therewith, a series of pins mounted on the chain and extending outward adapted for reception thereon of book-binding bushings, the median position of the chain on the belt providing substantial transverse first and second working areas on the belt on opposite sides of the chain, separate groups of guide lugs attached to the belt in said working areas respectively, members of the group of guide lugs in the first working area being adapted to locate marginally prepunched covers on said first working area for application of their punches to said bushings on said pins of the chain, members of the guide lugs in the second area being adapted to locate and guide marginally punched sheaves of prepunched pages for application of their punches to said pins above the said located covers, members of said lugs in the first working area being adapted also to receive and guide a second marginally punched cover for application of its punches to said bushings on said lugs above said sheaves of pages.

2. Book-binding apparatus comprising a first and a second pulley and an endless flexible belt trained around the pulleys, means adapted to drive the belt in an upper reach from the first to the second pulley, a flexible chain of pinned links affixed to the belt on its outside in a median plane thereof and adapted to travel and flex therewith, a series of pins mounted on the chain and extending outward adapted for reception thereon of book-binding bushings, the median position of the chain on the belt providing substantial transverse first and second working areas on the belt on opposite sides of the chain, separate groups of guide lugs adjustably attached to the belt in said working areas respectively, members of the groups of guide lugs in the first working area being adapted to locate marginally prepunched covers on said first working area for application of their punches to said bushings on said pins of the chain, support means at chain height within each group of guide lugs in the second area 35 adapted with the surrounding lugs flatwise to locate and guide marginally punched sheaves of prepunched pages for application of their punches to said pins above the said located covers, members of said lugs in the first working area being adapted also to receive and guide a second marginally punched cover for application of its punches to said bushings on said lugs above said sheaves of pages.

3. Book-binding apparatus made according to claim 2, including spring-stripping fingers arching over the belt on the second pulley, said fingers being transversely staggered with respect to said guide means and adapted to enter beneath said assemblies as carried upon said supports to strip the assemblies away from the supports and pins.
